VALVE CONTROL FOR INTERNAL-
COMBUSTION ENGINES

Percy E. Barker, Pepper Pike Village, Ohio

Application November 30, 1944, Serial No. 565,886

11 Claims. (Cl. 123—73)

The invention relates to improvements in valve control for internal combustion engines, and particularly to improvements of this character which effect a change in the timing of the feeding of the explosive mixture into the crank case and cylinder of two-cycle engines. More particularly, the invention effects in a new and improved manner an advance in such fuel feeding during a starting period of the engine and a return to normal feeding periods at any desired time subsequent to the starting of the engine. The invention is particularly applicable to model aeroplanes and other equipment using miniature motors, and to outboard motor boats.

As is well-known by those versed in the art, engines designed for high speed operation, such as the type of engines under consideration, are most effective, when operating normally or at high speeds, if the charge of explosive mixture is commenced to be drawn into the crank case somewhat subsequent to the passage of the axis of the crank-pin by its outer dead-center, and ceases to be so drawn somewhat subsequent to the passage of this axis by its inner dead-center. This angular advance of the crank pin axis for these mixture-feeding beginnings and endings is about 45°. However, when starting the engine, the comparatively slow speed thereof effects the drawing of exhaust or combusted gases back into the crank case if the periods of drawing in explosive mixture to the crank case and of shutting off the mixture are those above given for high speed engine operation.

This invention is designed to obviate the above-mentioned disadvantages by providing rapid easy starting of such high speed engines through a slip movement effected at will between the drive and fuel mixture feeding valve actuated thereby, this relative movement being effected before starting the engine by a clock-wise angular movement of the drive relative to the usual position of the valve ports, and then the imposition of a drag upon the movements of the valve ports after starting the engine to permit the drive to recover in a counter-clockwise direction the relative angularity previously lost and thus run normally relative to the valve ports.

The annexed drawings and the following description set forth in detail certain means illustrating the improvements in valve control for internal combustion engines, such disclosed means constituting, however, only one of the many forms in which the principle of the invention may be embodied.

In said annexed drawings:

Figure 1 is a section of the improved valve control axially of the crank shaft and cylinder of a two-cycle internal combustion engine to which the invention is applied, the plane of the section being shown by the line 1—1, Figure 2;

Figure 2 is a section taken in the planes indicated by the line 2—2, Figure 1;

Figures 3 and 4 are sections taken in the planes indicated by the respective lines 3—3 and 4—4, Figure 1;

Figure 5 is a section, similar to Figure 2, but on a smaller scale, showing the positions of the crank-pin and connecting rod at the commencement of mixture feed into the crank case, when starting the engine;

Figure 6 is a section through the crank-case, similar to Figure 4, showing the position of the ports forming the mixture inlet at the phase of a cycle shown in Figure 5;

Figure 7 is a section, similar to Figure 5, showing the position of the crank-pin and connecting rod at the time of shutting off the mixture feed into the crank case, when starting the engine;

Figure 8 is a section through the crank-case, similar to Figure 6, showing the position of the ports forming the mixture inlet at the phase of a cycle shown in Figure 7;

Figure 9 is a section, similar to Figure 5, showing the position of the crank-pin and connecting rod at the commencement of mixture feed into the crank-case when the engine is running normally or at high speed;

Figure 10 is a section through the crank-case, similar to Figure 6, showing the position of the ports forming the mixture inlet at the phase of a cycle shown in Figure 9;

Figure 11 is a section, similar to Figure 9, showing the position of the crank-pin and connecting rod at the time of shutting off the mixture feed into the crank-case, when the engine is running normally or at high speed; and

Figure 12 is a section through the crank-case showing the position of the ports forming the fuel inlet at the phase of a cycle shown in Figure 11.

Referring to the annexed drawings, in which the same parts are indicated by the same respective numbers in the several views, a cylinder 1 of an internal combustion two-cycle engine has a piston 2 working in a combustion chamber 3, and ignition means 4, the wall of the cylinder 1 being formed with an exhaust port 5. The cylinder 1 is mounted on the engine crank case 6, with the chamber 8 of which its chamber 3 has

communication through the angular mixture inlet passage 7 and port 7' thereof formed in the lower portion of the cylinder wall. The exhaust port 5 is uncovered by the reciprocatory movements of the piston 2 throughout substantially a 130° angular movement of a crank-pin 24, hereinafter more fully mentioned, and the inlet port 7' uncovered throughout substantially a 5% part of the period when the exhaust port 5 is uncovered, the port 7' thus being opened subsequent to the opening of the port 5 and being closed prior thereto.

One part of the crank case 6 (the left side shown in Figure 1) is a chambered interiorly end-flanged cylindrical formation 9 forming a cover and having a mixing chamber 11. Mounted in one side of this crank-case part 9 and on the end flange 9' thereof is an exteriorly end-flanged cylindrical valve housing 28 having a port 10 by which explosive mixture is admitted to a rotary sleeve valve 16, hereinafter more fully mentioned, the fuel entering said mixing chamber 11 from a depending fuel tank 15 by a conduit 13 controlled by an adjustable needle valve 14. Combustion air enters the mixing chamber 11 through an inlet end portion 12 of the crank-case formation 9.

The sleeve valve 16 is rotatably mounted in the cylindrical housing 28, is closed at its outer end by a plug 16', and opens at its inner end into the crank case chamber 8. The sleeve valve 16 has a port 17 which throughout 180° of the rotation of the valve 16 registers more or less with the port 10 of the housing 28 whereby to pass explosive mixture into the interior of the sleeve valve 16 and thence into the crank case chamber 8.

A second and right hand cover member 18, Figure 1, of the crank case 6 is coupled to the left hand cover 9 by an intermediate main crank-case part 19 which is a generally cylindrical formation providing a connecting rod chamber 20' and also a support 20² upon which the cylinder 1 is directly mounted. The connecting rod 20 is pivotally connected to the piston 2 by a wrist-pin 21 and to the crank-shaft 22 rotatably mounted in the crank-case part 19 by a crank plate 23 having a crank-pin 24.

The crank-pin 24 is formed with an outwardly-extended stud 25 which intersects an arcuate slot 32, Figure 3, formed in a disk 31 mounted on the inner end of and having a driving fit with the sleeve valve 16. The periphery of the disk 31 is a grooved formation 35 and in the groove thereof is mounted a spring wire 33, one end 36 of which is angularly bent to seat in a recess 37 of the disk 31, so that the disk 31 and the wire 33 are rotatably secured together. An intermediate portion of the spring 33 is bent so as to constitute a substantially straight section 34 thereof and this section 34 intersects the path of travel of the crank-pin stud 25 in the slot 32 of the disk 31. Spring stress is thus applied against the movement of the stud 25 in the slot 32 and this stress is sufficient to impose a drag upon such stud movement but not so heavy a drag but that relative movement of the disk 31 and the stud 25 can be readily effected by a manual turning of the crank-shaft 22 clockwise, when a manual drag is imposed upon the turning movement of the disk 31 by means hereinafter described. However, the rotation of the disk 31 is effected from the crank-pin 24 through the spring section 34, so that when the crank-pin 24 is in the relative angular position shown in Figure 2, the stud 25 will remain in the posi-

tion, relative to the slot 32, shown in Figure 2, when the crank-pin 24 is driving, the direction of driving being counterclockwise, and the manual drag on the movement of the disk being removed. An application of the drag during this counterclockwise movement will result in the stud 25 moving to the advanced end of the slot 32.

This drag upon or retardation of the turning of the disk 31 is effected by a button or plug 38, Figure 1, mounted in and outwardly extended from the crank-case part 9, passed through the valve housing 28, and adapted to have a dragging contact with the outer surface of an end extension 16² of the sleeve valve 16. Convenient operation of the button 38 is provided by a spring strip 39 mounted at one end in the housing for the needle valve 14, engaging the top of the button 38 intermediate its ends, and having a curved finger-engageable portion at its other end.

The type of engine illustrated is adapted for model aeroplanes and to that end the outer end of the crank shaft 22 has a reduced cylindrical end extension 26 serving as a propeller shaft to which the propeller (not shown) is secured by relatively adjustable clamping plates 27.

When the engine is running at its normal high speed, the fuel ports 10 and 17 come into registry, Figure 10, to commence to admit mixture to the sleeve valve 16 and, hence, to the crank-case chamber 8, after the crank-pin 24 and crank-pin stud 25 have passed their outer dead-center substantially an angular distance of 45°, Figure 9, after which these ports 10 and 17 continue to register to a greater or less extent for a crank-pin and sleeve valve movement of 180°, and then registration ceases when the crank-pin has passed its inner dead-center substantially 45°. At high speeds such a setting is suitable for best performance since, although the ports 10 and 17 are open to the crank-case chamber 8, after ignition, throughout a substantial part of the compressive movement of the piston 2, still the phases of the cycle follow so closely upon one another that there is no substantial passing of combustion products into the crank-case chamber 8.

However, when the engine is running comparatively slowly, as at starting, the setting just described retains the registration of the ports 10 and 17 too long after the piston 2 has commenced its inward stroke, resulting in the passing of combustion products back into the crank-case chamber 8. Therefore, this invention is designed to build up or increase the pressure in the crank-case chamber 8 by replacing, at an earlier phase of the cycle, the mixture passing therefrom into the cylinder 1 with fresh mixture, and then closing the port 17 at an earlier phase of the cycle. The invention also prevents a blow-back from the crank-case chamber 8 during the initial compression effected therein by the descent of the piston 2. These advantages are obtained by advancing the registry period of the mixture ports 10 and 17 relative to the angular position of the crank-pin 24. The manner in which this is done and also the manner of returning to the normal setting for high speed operation are as follows;

Before starting the engine, the button 38, Figure 1, is depressed by finger pressure upon the spring strip 39 sufficient to prevent the disk 31 from being turned by a movement of the wrist-pin stud 25 acting through the spring portion 34, Figure 3. It may be stated that the wrist-

pin stud 25 is at this time at the opposite end of the slot 32 from that in which it is shown in Figure 3. That opposite end of the slot 32 is where the wrist-pin stud 25 was positioned when the engine was previously shut off. The function of the wrist-pin stud 25 is, as is well understood, to drive against the forward wall of the slot 32 during normal running of the engine. Then, with the disk 31 thus restrained, the crank-shaft 22 is turned in a clockwise direction causing the wrist-pin stud 25 to move to the opposite end of the slot 32, i. e., the end shown in Figure 3, the stress of the spring portion 34 upon the stud 25 being less than the drag imposed upon the disk 31 through the button 38 so that the disk 31 is not moved by the clockwise movements of the crank-shaft 22 and the stud 25. This operation effects an advance in the time of registry of the mixture ports 10 and 17 relative to the angular position of the wrist-pin stud 25. Then the button 38 is released and the propeller flipped counterclockwise to start the engine, and the stud 25 drives the disk 31 and, hence, the sleeve valve 16 through the spring portion 34, thus maintaining the advanced position of the valve port 17. When the engine is running normally, or at any suitable desired time, the button 38 is again depressed to place a drag upon the rotating disk 31 until the stud 25, which is turning at a speed determined by the impulses from the cylinder, pushes by the spring portion 34 and advances relative to the disk 31, and, hence, advances angularly relative to the time of registry of the ports 10 and 17. When the stud 25 reaches the forward end of the slot 32, it drives the disk 31 at its own speed and the drag imposed by the button 38 on the sleeve 16 is ineffective, and the button 38 is released. The angular relation of the crank-pin driving stud 25 to the mixture feeding period into the crank-case chamber 8 is then that suitable for normal engine operation.

In addition to the building up of the pressure in the crank-case 8 by the apparatus and method of working the same hereinbefore described, a collateral benefit arises from the fact that a blow-back of the mixture through the open end of the valve 16 and through the mixing chamber 11 is eliminated. This blow-back upsets good mixture conditions. A well-mixed shot which is ready for admission to the cylinder 1 is destroyed and what immediately subsequently replaces it and is fed into the cylinder 1 is poor mixture.

Particular emphasis is placed upon the fact that the nozzle 13 and the vaporizing arrangement of the chamber 11 are positioned below the level of the valve 16 and the inlet to the crank-case chamber 8. This arrangement minimizes flooding at starting. The excess fuel drains away from the valve 16. Oftentimes, manually or otherwise, the air inlet 12 will be more or less completely shut off at starting and a rich mixture admitted which, if it does not drain away, will induce a long-time stalling period in which a very wet and globular mixture is fed, which wet mixture must be dried out before the engine will start. The drainage arrangement mentioned obviates or quickly clears up the disadvantages mentioned.

It will be noted in Figure 3 that there are an additional arcuate slot 32' and a deformed spring portion 34' intersecting the slot 32', which are diametrically opposed to the slot 32 and the spring portion 34. In addition to balancing the weight of the disk 31, the provision of this additional slot and deformed spring portion permits running of

the engine with the cylinder 1 either upright or upside down and still preserves the proper timing of fuel feed and the location of the fuel tank 15 in a dependent position. To change from an upright position to a dependent position of the cylinder 1, the crank-case cover 9 is loosened from the crank-case 6 and the stud 25 from the slot 32, and the crank-case cover 9 and crank-case 6 then reassembled with the cylinder 1 and the tank 15 both on the bottom and with the stud 25 intersecting the slot 32', thus preserving the beginning phase of the entry of mixture into the crank-case chamber 8, or the beginning of registration of the ports 10 and 17, for the time when the crank-case pin 25 is at outer dead center, for starting, and is substantially 58° beyond outer dead center, for normal running.

What I claim is:

1. A valve control for internal combustion engines comprising relatively movable elements formed with registrable ports providing a fluid inlet, driving means for moving one of the elements in cycles to cover and uncover the inlet, and selective means operable at will upon the driving means and said one element respectively to produce a drag upon said one element and a slip movement between the driving means and said one element whereby the inlet covering and uncovering phases of a cycle are shifted.
2. A valve control for internal combustion engines comprising relatively movable elements formed with registrable ports providing a fluid inlet, a crank-shaft and crank-actuating one of the elements in cycles to cover and uncover the inlet, including slip movement means between the crank and said one element, and means for imposing a drag on the movement of said one element to permit the slip movement means to function.
3. A method of varying the feeding periods of a combustible mixture, said method being worked in an internal combustion engine having a cylinder formed with an exhaust port, a reciprocable piston therein, ignition means, a crank-case having a mixture chamber portion communicating with the cylinder, the piston movements controlling the exhaust port and the communication between the cylinder and said chamber, the mixture chamber having a mixture inlet port, a sleeve rotatable in the mixture chamber and having a port registrable with the mixture chamber port to form an inlet to the mixture chamber, a crank-shaft and a crank for rotating the sleeve, and a connecting-rod mounted on the crank and actuating the piston, said crank and sleeve having a controlled limited relative angular movement, which method consists in turning the crank in one direction through such angular movement relative to the sleeve while restraining the latter from moving, then starting the engine with the restraint removed so that the crank and sleeve rotate together in the opposite direction in their changed relative angular positions, and then retarding the rotation of the sleeve while the crank moves forwardly relatively thereto through the angle of relative movement.
4. A valve control for internal combustion engines comprising a cylindrical casing having a port, a sleeve valve rotatably mounted in the casing and having a port registrable with the casing port, a disk rotatably secured to the sleeve, a rotatable crank-shaft, crank and crank-pin, the disk being driven by the crank-pin, means providing a slip movement in the rotatability of the disk by the crank-pin, and manually-operable

means for imposing a drag on the rotation of the disk to permit such slip movement to be effected.

5. A valve control for internal combustion engines comprising a cylindrical casing having a port, a sleeve valve rotatably mounted in the casing and having a port registerable with the casing port, a disk rotatably secured to the sleeve, a rotatable crank-shaft, crank and crank-pin, the disk having an elongated arcuate slot intersected by the crank-pin, a spring member secured to the disk, rotatable therewith, and having a deformable portion thereof intersecting the path of movement of the crank-pin in the slot and of sufficient resistance to deformation to produce normal rotation of the disk through the spring, and manually-operable means for imposing a drag on the rotation of the sleeve to permit movement of the pin in the slot against the resistance of the deformable spring portion.

6. A valve control for internal combustion engines comprising a cylindrical casing having a port, a sleeve valve rotatably mounted in the casing and having a port registerable with the casing port, a disk rotatably secured to the sleeve, a rotatable crank-shaft, crank and crank-pin, the disk having an elongated arcuate slot intersected by the crank-pin, a spring wire peripherally mounted on the disk, having an end secured in the body of the latter, and having an intermediate portion thereof intersecting the path of movement of the crank-pin in the slot and of sufficient resistance to movement outwardly of the disk periphery to produce normal rotation of the disk through the spring, and manually-operable means for imposing a drag on the rotation of the sleeve to permit movement of the pin in the slot against the resistance of the spring.

7. A valve control for internal combustion engines comprising a cylindrical casing having a port, a sleeve valve rotatably mounted in the casing and having a port registerable with the casing port, a disk rotatably secured to the sleeve, a rotatable crank-shaft, crank and crank-pin, the disk having a plurality of elongated arcuate slots spaced apart equal angular distances and adapted to be intersected by the crank-pin, a spring member secured to the disk, rotatable therewith, and having deformable portions thereof intersecting the respective paths of movement of the crank-pin in the respective slots and of sufficient resistance to deformation to produce normal rotation of the disk through the spring, and manually-operable means for imposing a drag on the rotation of the sleeve to permit movement of the pin in the slot against the resistance of the deformable spring portions.

8. A valve control for internal combustion engines comprising a cylindrical casing having a port, the casing having a mixture chamber formed therein below and communicating with the port and an air inlet to the chamber, a fuel tank mounted on the casing and having controlled communication with the mixing chamber, a sleeve valve rotatably mounted in the casing and having a port registerable with the casing port, a disk rotatably secured to the sleeve, a rotatable crank-shaft, crank and crank-pin, the disk being driven by the crank-pin, means providing a slip movement in the rotatability of the disk by the crank-pin, and manually-operable means for imposing a drag on the rotation of

the disk to permit such slip movement to be effected.

9. A valve control for internal combustion engines comprising a cylindrical casing having a port, the casing having a mixture chamber formed therein below and communicating with the port and an air inlet to the chamber, a fuel tank depending from the casing and having controlled communication with the mixing chamber, a sleeve valve rotatably mounted in the casing and having a port registerable with the casing port, a disk rotatably secured to the sleeve, a rotatable crank-shaft, crank and crank-pin, the disk being driven by the crank-pin, means providing a slip movement in the rotatability of the disk by the crank-pin, and manually-operable means for imposing a drag on the rotation of the disk to permit such slip movement to be effected.

10. A valve control for internal combustion engines comprising a cylindrical casing having a port, a sleeve rotatably mounted in the casing and having a port registerable with the casing port, the sleeve having an extended end portion upon which a disk is secured, a rotatable crank-shaft, crank and crank-pin, the disk being formed with an arcuate slot adjacent its periphery intersected by the crank-pin to drive the disk and, hence, rotate the sleeve by the engagement of the pin with an end wall of the slot, the disk being formed with a peripheral groove in which is mounted a spring wire having a portion thereof intersecting the path of movement of the crank-pin in the slot, one end of the spring wire being secured to the body of the disk, the spring wire being of sufficient resistance to movement outwardly of the disk periphery to produce normal rotation of the disk through the spring, and manually-operable means for imposing a drag on the rotation of the sleeve whereby a turning of the crank-shaft in one direction can overcome the wire resistance to permit movement of the crank-pin in the slot, and whereby a driving by the crank-shaft can effect a movement of the crank-pin in the slot in the opposite direction.

11. A method of varying the feeding periods of a combustible mixture, said method being worked in an internal combustion engine having a cylinder formed with an exhaust port, a reciprocable piston therein, ignition means, a crank-case having a mixture chamber portion communicating with the cylinder, the piston movements controlling the exhaust port and the communication between the cylinder and said chamber, the mixture chamber having a mixture inlet port, a sleeve rotatable in the mixture chamber and having a port registerable with the mixture chamber port to form an inlet to the mixing chamber, a crank-shaft and a crank for rotating the sleeve, and a connecting-rod mounted on the crank and actuating the piston, said crank and sleeve having a limited relative angular movement, which method consists in turning the crank in one direction through an angular movement relative to the sleeve, then starting the engine with the crank and sleeve connected so that they rotate together in the opposite direction in their changed relative angular positions, and then imposing a drag upon the rotation of the sleeve while the crank moves forwardly to its original position relatively thereto.

PERCY E. BARKER.
